[54] FLAT TO SPIRAL LIGHT SET

5,639,157 6/1997 Yeh 362/123
5,664,877 9/1997 Wu ..... 362/252[75] Inventor: **Najeh Rahman**, Monsey, N.Y.Primary Examiner—Susan J. Lucas
Attorney, Agent, or Firm—Amster, Rothstein & Ebenstein[73] Assignee: **Minami International Co.**, Yonkers, N.Y.

[57] CLAIM

[**] Term: **14 Years**

The ornamental design for a flat to spiral light set, as shown and described.

[21] Appl. No.: **29/097,719**

DESCRIPTION

[22] Filed: **Dec. 10, 1998**

FIG. 1 is a top plan view of a flat to spiral light set in its flat orientation showing my new design.

[51] LOC (6) Cl. **26-04**

FIG. 2 is a side elevational view thereof;

[52] U.S. Cl. **D26/25**

FIG. 3 is a side elevational view thereof in its spiral orientation; and,

[58] Field of Search D26/25; D11/117, D11/118; 362/252, 250, 249, 806, 123

FIG. 4 is a side elevational view thereof similar to FIG. 3, but rotated 90°.

[56] References Cited

In FIG. 1 an electric plug is illustrated in phantom line as environment only and not forming any part of the claimed design.
